CLAIM

The ornamental design for a ball carrier, as shown and described.

DESCRIPTION

FIG. 1 is a top plan view of a ball carrier showing the first embodiment of the design;

FIG. 2 is a top plan view of a ball carrier showing a second embodiment of the design, the sole difference being the omission of the transparent netting disposed in the front and rear portions of said carrier;

FIG. 3 is a bottom plan view of said first embodiment of the design;

FIG. 4 is a bottom plan view of said second embodiment of the design;

FIG. 5 is a front elevational view of said first embodiment of the design;

FIG. 6 is a front elevational view of said second embodiment of the design;

FIG. 7 is a rear elevational view of said first embodiment of the design; and,

FIG. 8 is a rear elevational view of said second embodiment of the design.
